UNITED STATES PATENT OFFICE

98,281

DESIGN FOR A TAG

Alice H. Thorsen, New York, N. Y.

Application December 11, 1935, Serial No. 60,004

Term of patent 3½ years

To all whom it may concern:

Be it known that I, Alice H. Thorsen, a citizen of the United States of America, residing in Manhattan, county of New York, and State of New York, have invented a new, original, and ornamental Design for a Tag, of which the following is a specification, reference being had to the accompanying drawing, forming part thereof, wherein,

The cross-hatched area extending from beneath the overlapping front portion of the tag, represents a swatch.

I claim:

The ornamental design for a tag, substantially as shown, and described.

ALICE H. THORSEN.
